(57) **CLAIM**

The ornamental design for an aquarium cleaner, as shown and described.

DESCRIPTION

FIG. 1 is a perspective view of an aquarium cleaner showing my new design;

FIG. 2 is a front view thereof;

FIG. 3 is a rear view thereof;

FIG. 4 is a side view thereof;

FIG. 5 is the opposite side view of FIG. 4 thereof;

FIG. 6 is a top view thereof; and,

FIG. 7 is a bottom view thereof.

The broken lines shown in the figures are included for the purpose of illustrating portions of the aquarium cleaner and form no part of the claimed design.
